per Mann Atty's.

JOHN C. BRAIN, OF BROOKLYN, NEW YORK.

Letters Patent No. 86,727, dated February 9, 1869.

IMPROVED HEAT-RETAINING PAIL.

The Schedule referred to in these Letters Patent and making part of the same.

To all whom it may concern:

Be it known that I, JOHN C. BRAIN, of Brooklyn, in the county of Kings, and State of New York, have invented a new and useful Improvement in Heat-Retaining Pails; and I do hereby declare that the following is a full, clear, and exact description thereof, which will enable others skilled in the art to make and use the same, reference being had to the accompanying drawing, forming part of this specification.

This invention relates to an improvement in pails, such as are employed by laborers for carrying their dinners; and

It consists in preventing the radiation of heat from the pail, by protecting or surrounding it with a non-conducting medium, so that the heat imparted to the contents of such pail may be retained for many hours, as will be hereinafter described.

The accompanying drawing represents a vertical section of a pail constructed according to my invention.

In carrying out my invention, I form the pail with double walls, and double bottom and top, or cover, and fill the space between the walls with a combination of felt and paper, or with felt, and with a substance known as paper felt, and with one or more layers of paper combined therewith.

A is the outer wall, which may be made of tin or other metal.

B represents the inner wall, which may be composed of any suitable material.

The bottom, C, and the top, D, are formed and protected in the same manner.

E is an inner cover to the pail.

F represents the interior of the pail.

The two outer layers of the non-conducting medium, represented by g, are composed of paper felt, that is, paper-pulp, combined with wool fibre, the materials being combined by "felting" in the ordinary manner.

h represents a thick layer of wool felt.

The next two layers are paper felt, the same as g, and are marked i, while the inner layer, j, represented by the yellow line, is ordinary paper.

A pail, thus surrounded and protected, will retain the heat of the contents for many hours, (eight or ten,) when the contents, as liquids or other articles, have been raised to the boiling-point.

I do not confine myself to the particular arrangement of the layers of the non-conducting material, nor to the particular number of each layer. The principal object I have in view is to provide a pail, for laboring men, which will enable them to partake of a warm dinner in the wood, field, or elsewhere.

Having thus described my invention,

I claim as new, and desire to secure by Letters Patent—

As a new article of manufacture, a dinner-pail, surrounded by different layers of felt or felt paper, g i, the wool-felt filling h, and the paper layer j, as and for the purpose herein shown and described.

JNO. C. BRAIN.
